United States Patent Office

Des. 208,178
Patented July 25, 1967

208,178

COMBINATION SERVING TABLE AND HOOD

Alvin Carroll Meyer, Parkville, Mo., assignor to The Gold Buffet Franchise, Inc., North Kansas City, Mo., a corporation of Missouri

Filed Mar. 21, 1966, Ser. No. 1,549

Term of patent 14 years

(Cl. D81—10)

Fig. 2.

Fig. 3.

FIG. 1 is a perspective view of a combination serving table and hood embodying my design. The opposed side and end of each of the serving table and hood are mirror images of those illustrated.

FIG. 2 is an end elevational view thereof.

FIG. 3 is a top plan view thereof.

I claim:

The ornamental design for a combination serving table and hood, as shown and described.
